UNITED STATES PATENT OFFICE.

ARTHUR CLEVELAND, OF AUGUSTA, ARKANSAS.

COMBINATION UMBRELLA AND CANE.

1,340,375.

Specification of Letters Patent. Patented May 18, 1920.

Application filed February 17, 1920. Serial No. 359,434.

To all whom it may concern:

Be it known that I, ARTHUR CLEVELAND, a citizen of the United States, residing at Augusta, in the county of Woodruff, State 5 of Arkansas, have invented a new and useful Combination Umbrella and Cane; and I do hereby declare the following to be a full, clear, and exact description of the invention, such as will enable others skilled in 10 the art to which it appertains to make and use the same.

The invention relates to combined umbrella and walking canes and has for its object to provide a walking cane having 15 telescopically disposed therein an umbrella, which umbrella, if desired to use the same may be easily and quickly removed from the cane, the cane inverted so as to form the handle member for the umbrella and the 20 umbrella stick inserted in the inverted upper end of the cane and held therein, so that the umbrella may be opened and used.

A further object is to provide a combined umbrella and cane comprising a tubular 25 member, one end of said tubular member being split and receiving an enlarged end of a second tubular member, said second tubular member being provided with means for holding an umbrella stick which carries an 30 umbrella when in folded position which is disposed within the tubular member of the cane. Also to provide means whereby the tubular member which carries the umbrella may be detached, the umbrella removed 35 from the tubular body member, the tubular body member which carries the umbrella inverted and its tapered end held in the end of tubular body member from which it has been removed so that the umbrella may be 40 opened and used.

With the above and other objects in view the invention resides in the combination and arrangement of parts as hereinafter set forth, shown in the drawings, described and 45 claimed, it being understood that changes in the precise embodiment of the invention may be made within the scope of what is claimed without departing from the spirit of the invention.

50 In the drawings:—

Figure 1 is a side elevation of the device showing the same in the form of a cane.

Fig. 2 is a side elevation of the device showing the same after it has been formed 55 into an umbrella.

Fig. 3 is a detail sectional view taken on line 3—3 of Fig. 1.

Fig. 4 is a side elevation of the device showing the umbrella carrying tubular member after the same has been removed 60 from the body of the cane, the umbrella open and the tubular member slid upwardly to its second notch, so that it can be received by the body tubular member when the same is inverted.

Fig. 5 is a side elevation of the tubular body member.

Fig. 6 is a detail sectional view taken on line 6—6 of Fig. 2.

Fig. 7 is a detail sectional view of one of 70 the retaining sleeve.

Fig. 8 is a detail view of the handle member.

Referring to the drawings the numeral 1 designates a tubular body member which 75 when the device is in the form of a cane as shown in Fig. 1, or when it is in the form of an umbrella as shown in Fig. 2, forms a body member for the cane, or a staff for the umbrella, to which a handle may be attached. 80 By referring to Figs. 1 and 3 which show the device in the form of a cane, it will be seen that a tapered tubular section 2 provided with a large cylindrical head 3 is provided. The head 3 is disposed in the split 85 end 4 of the member 1 in the lower end of the chamber 5 of said tubular member 1, said enlarged portion 3 being held in the split end 4 by means of a tapered threaded sleeve 6, which threads on the lower end of 90 the tubular member 1 and forces the segments formed by the splits into engagement with the enlargement 3. Tubular member 2 at its enlarged end receives and frictionally holds a slid able sleeve 8, which sleeve is held 95 in its down position by a spring detent 9 of the umbrella stick 10, which co-operates with an aperture 11 in the sleeve 8. The umbrella stick 10 being provided with a conventional form of umbrella 12 which is 100 adapted to be raised, the stays 12^a being pivotally connected to the sleeve 8. The upper end of the umbrella stick 11 and the umbrella 12 is disposed in the chamber 5 of the tubular member 1 when the device is in the 105 form of a walking cane. The upper end of the tubular member 1, when the device is in the form of a walking cane, is provided with a handle member 13, there being a tapered threaded sleeve 15 similar to sleeve 110

6 threaded on the upper split end of the tubular member 1 as shown in Fig. 6. The umbrella stick is also provided with a detent 16 which engages the aperture 11 in the sleeve 8 when the device is used as an umbrella.

When it is desired to convert the cane into an umbrella, the sleeve 6 is unscrewed, then the operator grasps the tubular section 2 and removes the umbrella and its stick from the end of the tubular body member 1. The operator then places the member 2 in body member 1 in the position as shown in Fig. 6, after which as he forces the umbrella stick downwardly the umbrella will be raised. This downward movement of the stick being continued until the detent 16 engages the aperture 11 in the sleeve 8. Then the sleeve 15 and the sleeve 6 are screwed onto the ends of the tubular member 1 so that the split ends thereof will be forced inwardly. The split ends at the upper end of the tubular member being forced into frictional engagement with the enlargement 3 of the tubular member 2, thereby holding said tubular member 2 against displacement.

When it is desired to convert the umbrella back into a cane, the operation is the reverse to the one set forth above.

From the above it will be seen that a combination umbrella and cane is provided wherein the converting of a cane into an um-

rella or an umbrella into a cane may be quickly accomplished and one wherein the device, either as a cane or umbrella is compact, simple of construction and free from clumsiness, which is the principal objection to devices of this character now on the market.

The invention having been set forth what is claimed as new and useful is:—

A combined umbrella and walking cane comprising a tubular member, said tubular member having its ends vertically split and threaded, tapered sleeves threaded on said split and threaded ends of the tubular member, a tapered tubular member disposed in said first mentioned tubular member, an umbrella carrying stick slidably mounted in the tapered tubular member, said threaded sleeves on the ends of the first mentioned tubular member forming means whereby the enlarged end of the tapered tubular member may be frictionally held in the upper end of the first mentioned tubular member or in the lower end thereof.

In testimony whereof I have signed my name to this specification in the presence of two subscribing witnesses.

ARTHUR CLEVELAND.
